UNITED STATES PATENT OFFICE.

THEODORE O. BITTNER, OF BROOKLYN, NEW YORK.

CARD-SUPPORT.

1,135,874.

Specification of Letters Patent. Patented Apr. 13, 1915.

Application filed July 13, 1912. Serial No. 709,287.

To all whom it may concern:

Be it known that I, THEODORE O. BITTNER, a citizen of the United States, residing at Brooklyn, in the county of Kings and State 5 of New York, have invented new and useful Improvements in Card-Supports, of which the following is a specification.

The general object of the invention is to admit of supporting a show or display card 10 when the same is arranged in an upright or inclined position and bearing on one of its edges, and this without disclosing the support to those observing the front of the card. And to this end the invention consists in a 15 knee-down support or easel formed from a blank of suitable material such as card board and arranged so that when in set-up position it will support a display card at a required angle and be held against accidental toppling.

Other objects will appear and be better understood from that embodiment of my invention of which the following is a specification, reference being had to the accompanying drawings forming part hereof, in which:

Figure 1 is a perspective of the device in set-up position. Fig. 2 is a rear elevation. Fig. 3 is a plan of the blank and showing the 30 device collapsed.

The blank *a* may be formed of any material found suitable for the purpose, such as heavy card or paste board. By preference the blank is formed with a central bearing 35 portion 5 which extends longitudinally of the blank and foldable wing portions 6—6 whose outer sides 7—7 extend obliquely to the opposite sides of the bearing portion 5, whereby to admit of having at the upper 40 end of the bearing portion 5, a tab 8 of minimum length, which may be connected to a hook or the like driven into a wall or other upright support. When the tab is connected to a hook, the bearing portion 5 will 45 be held at an angle to the vertical and such angle will be different from that which the said bearing portion will have when the device is resting on the lower edges 9—9 of the wings, since, as shown in Fig. 3, the angle of 50 those edges to the sides of the bearing portion 5, is not complementary to that which the sides 7—7 make with the sides of the bearing portions. The foldable locking tongue 10 is connected at one end to the bearing portion 5 and when folded rearwardly 55 between the wings 6—6, leaves an opening

11 in the bearing portion 5 as shown in Figs. 1 and 2. The lateral extensions 12—12 at the outer corners of the locking tongue, have notches 13—13 made to receive the sides 7—7 60 of the wings and detents 14—14 formed in the said sides, as shown in Figs. 1 to 3 inclusive.

When it is desired to set up the device from the position shown in Fig. 3, the tongue 65 10 is folded rearwardly and upwardly until a sufficient clearance is provided to admit of folding the wings 6—6 rearwardly and at approximately right angles to the bearing portion 5. When the wings are thus folded 70 they will bear on the opposite sides of the tongue and the sides 7—7 will be presented to the notches 13—13. The tongue may now be folded downwardly whereupon the sides 7—7 will pass into the notches 13—13. 75 The downward movement of the tongue is continued until the notches thereof are at the middle of the detents 14—14 in which position the tongue will be interlocked with the wings 6—6 and held against further 80 downward movement by the lower sides of the detents. When it is desired to unfold or knock down the device the tongue is moved upwardly until the notches 13—13 are beyond the sides 7—7 whereupon the wings 85 may be folded into the plane of the bearing portion 5. In this last-named position the device will be perfectly flat, whereby a considerable number of such devices may be packed into a relatively small space. 90

By reference to Fig. 1 of the drawing it will be seen that the wing portions 6 are provided with straight edges 15 located at the upper portion of the opening 11 and the said straight edges are approximately at 95 right angles to the lower edge 9. The said wing portion 6 are also provided with other straight edges located at the lower portion of the opening 11. The last mentioned straight edges are approximately at a right angle to the plane of the central portion 5 of the support. Consequently when the support is hung up by the tap 8 a card or other flat object may be placed on edge on the straight edges 15 and the edges 15 will hold 100 the said card so that it may be readily seen while resting upon the support. 105

What is claimed as new is:

A support having an intermediate portion provided with angularly disposed wing portions located at the side edges thereof, said intermediate portion being provided between 110

its ends with an opening, the wing portions having recesses communicating with the opening in the intermediate portion, the uppermost edges of said recesses being straight and disposed approximately at right angles to the lower edges of the wing portions the lower edges of said recesses being disposed approximately at right angles to the plane in which the intermediate portion lies, the

spaces between the straight edges forming ¹⁰ openings in which articles may be received and supported.

In testimony whereof I affix my signature in presence of two witnesses.

THEO. O. BITTNER.
